CLAIM

The ornamental design for a grip assist cuff with pad, as shown and described.

DESCRIPTION

FIG. 1 is a bottom view of the grip assist cuff with pad shown in accordance with the invention.

FIG. 2 is a top view of the pad.

FIG. 3 is a left side view of the pad.

FIG. 4 is a right side view of the pad.

FIG. 5 is a front end view of the pad.

FIG. 6 is a rear end view of the pad.

FIG. 7 is a top view of the pad worn on a left hand of a user.

FIG. 8 is a bottom view of the pad on a left hand of a user.

FIG. 9 is an isometric view of the pad being worn on the right hand of a user gripping a weight lifting bar with grip assist portion being wrapped around the bar.

FIG. 10 is an isometric view of the pad being worn on a right hand of a user showing how the grip assist portion is free to move away from the user's palm and fingers; and,

FIG. 11 is an isometric view of the pad being worn on a right hand of a user showing how the freely moving grip assist portion (shown in FIG. 10) can be utilized in alternative grip configuration, that is.

The broken lines illustrate environment that forms no part of the claimed design.
